UNITED STATES PATENT OFFICE.

CHARLES F. FISHER, OF JAMAICA, NEW YORK.

DESIGN FOR AN ASH-RECEIVER.

47,749.

Specification for Design.

Patented Aug. 24, 1915.

Application filed April 6, 1915. Serial No. 19,558. Term of patent 3½ years.

To all whom it may concern:

Be it known that I, CHARLES F. FISHER, a subject of the Emperor of Germany, residing at Jamaica, in the county of Queens and State of New York, have invented a new, original, and ornamental Design for Ash-Receipters, of which the following is a specification, reference being had to the accompanying drawing, forming part thereof.

The figure is a perspective view of an ash receiver, showing my new design.

I claim:

The ornamental design for an "ash receiver," as shown.

CHARLES F. FISHER.
